UNITED STATES PATENT OFFICE.

EDWARD H. PENCE, OF PORTLAND, OREGON.

MANUFACTURE OF TRANSPARENCIES.

Application filed April 28, 1922. Serial No. 557,112.

My invention relates to the manufacture of ornamental transparencies for artistic and decorative purposes.

The principal object of my invention is to effect a manufacture, including an art and its product, of a transparent or translucent composite sheet comprising in its make up small particles of transparent or translucent substances such, for example, as marine or other shells, arranged in any suitable and preferred design, and preferably combined with intermediate particles of preferably translucent material, as for example, crushed or powdered glass, in any variety of form and color desired, the same being massed and united by a suitable cement, preferably of a transparent or invisible kind.

I have discovered that many varieties of sea shells which ordinarily present a drab and dull appearance may be made freely translucent by removal of their natural outer coating, or the leathery skin that covers them and that after such treatment they develop upon passage of light through them colors of extraordinary beauty, even though after the treatment, without illumination, their exterior may be little changed in appearance from what it was before treatment.

Their nature renders some shells available for such ornamental use even without treatment, under any condition which will afford a light bright or strong enough to develop to the eye their latent beauties. Besides, in the choice and arrangement of the individual constituent elements of my manufacture, a fruitful field for the exercise of the artistic faculty is presented.

My invention contemplates the manufacture of composite sheets of the general description above given, which, without impairment of their beauty for use as transparencies, may be strengthened by being built upon a plate, or between plates of transparent homogeneous material, such for example as ordinary sheet glass.

Other objects of my invention will be apparent from the following specification wherein what constitutes my invention is first described in detail and then succinctly set forth in the appended claims.

In the accompanying drawing I illustrate, for the purpose of exemplification only, a lamp shade which comprises a series of

transparent panels each embodying my invention and collectively united by a metallic frame into a whole.

In said drawing,

Figure I is a side elevation of an ornamental lamp shade which comprises in each panel thereof a form of embodiment of my invention.

Figure II is a transverse section of a fragment of a composite sheet illustrating my invention in simplest form of embodiment.

Figure III is a similar view of a modification of my invention to the extent of an addition to and incorporation with my composite sheet as shown in Figure II, of a single transparent sheet of glass said glass sheet being used as a supporting plate or backing to the composite sheet.

Figure IV is a similar view of a further modification in which my simple sheet shown in Figure II is enclosed between two transparent sheets, and is incorporated therewith into a unitary article of manufacture.

Referring to the numerals on the drawing, 1 indicates the lower rail of a lamp shade frame which is united to a head 2, as by a partition strip 3. The parts 1, 2, and 3, in combination are an example only of one form of structure to which my invention may be usefully applied. Adjacent strips 3 unite with the members 1 and 2 to define a frame for the accommodation of a panel 4. My invention is concerned only in the panel and its method of manufacture. The panel is representative of a composite sheet or mass of any desired shape, dimensions, and exterior contour. As such it is intended to include any article of the class indicated from smallest to largest sizes, as, for instance, the tiniest mural ornament or "jewel" to large screens or window lights.

The panel 4, besides being of the representative capacity indicated above, includes in its composition the use of individual natural shells 6, whereof a number are arranged around a central shell 7 to constitute the central and most conspicuous subordinate design of the panel.

Repeating that the design itself constitutes no part of my present invention, it is specified that small translucent articles, as for example shells 6 and 7 denominated coarser ingredient, are united with preferably trans-

parent or translucent particles 8, which I denominate an "intermediate ingredient," into a stable mass by the aid of a suitable cement, of which, it being preferably of the 5 "invisible" kind, no attempt at illustration is made.

The intermediate ingredient 8 may consist, for example, of glass or quartz, or silica, or shells, or the like, and may vary 10 in degree of comminution, from that of the size of a pea or even in some cases something larger, to the fineness of grains of sand or finer.

If desired, some of the particles used in 15 my composite sheet may be opaque, and even bright metal may, in some instances, be used with pleasing effect. The general effect of the coarse and intermediate ingredients is always, nevertheless, that of a transparency.

A suitable cement for the purpose of my invention is found, for example, in an article now obtainable in the market under the commercial name "Dupont cement" and 25 which is both waterproof and transparent.

Of such shells as I use for my purpose, some may be found that are immediately available for use in their natural state; but many of the most beautiful specimens are, 30 in their natural state, substantially opaque. I have found that in a large class their opacity is due to the presence upon them of an outside leathery natural coating. Such coating is removable by the application of a 35 suitable acid bath, as, for example, one of dilute hydrochloric acid. The kind of acid and its degree of dilution may be varied, respectively, to a considerable extent for the treatment of different shells.

40 After preparing the shells, I assemble them in edgewise formation upon the surface of any suitable supporting body, preferably as specified in the next paragraph below, upon a sheet of glass 9, as is clearly 45 illustrated in Figure III of the drawing, and unite them together by the application of cement as already specified. If the cement alone is relied upon to unite the shells permanently, the resultant manufacture will 50 appear in cross section, as in Figure II. If they are permanently mounted on a glass sheet 9, the article so produced will appear as shown in Figure III, and if they are assembled and enclosed between two sheets of 55 glass, the article produced will be that shown in cross section in Figure IV.

Experiment and actual use have demonstrated that it is altogether practicable to 60 construct substantially in the manner described a stable, strong, and stiff composite sheet made from the ingredients specified, to wit, shells, or other suitable substance, "intermediate ingredient", and cement. Such a sheet may be, therefore, regarded as presenting the product of my invention in its sheet or mass composed of separate parti-

simplest form of embodiment; but for some uses it may be desirable to substitute for said simple form of sheet one incorporated with a supporting sheet or backing 9 (Figure III), which may be made of any suitable transparent material, such for example as glass. Furthermore, if desired, the said simple form of my sheet may be flanked on opposite sides by sheets 10 and 11, respectively, which are in effect, duplicates of the 70 sheet 9.

When sheets 9, or 10 and 11, as above specified are employed, they are by the aid of cement incorporated with my simple sheet and in effect made part of one unitary 80 structure or article of manufacture.

Besides the additional strength contributed by employment of backing or supporting plates represented by sheets 9, or 10 and 11, there is one distinct advantage obtained 85 in the use of it or them, namely, the smoothness of exterior surface that facilitates removal of dust or dirt therefrom.

In carrying out my process of manufacture, selection by color, size and configuration of the constituent elements to be used is carefully made, the color of the shells, if used, being preferably first developed if necessary in order to such selection. Afterwards the said elements may be arranged according to the design adopted, whatever it may be, and finally the cement is applied to unite the elements into one common mass. The order of manipulation of the several elements may, of course, be varied according 90 to the convenience and preference of the artist or workman. If a backing sheet 9, 10 or 11 is used, it is employed for setting the pattern of the selected design upon it, and becomes, upon application of the cement, 95 a constituent element of the completed article.

What I claim is:

1. The art of manufacturing transparencies which consists in incorporating according to a preconceived design, coarse and intermediate ingredients respectively permeable to light to constitute a composite self-sustaining mass.

2. The art of manufacturing transparencies which consists in incorporating by the aid of cement translucent shells disposed in correlative edgewise assemblage with a translucent intermediate ingredient, to constitute a composite sheet.

3. The art of manufacturing transparencies which consists in chemically removing from shells their outside natural coating, to render them permeable to light, and then incorporating them by the aid of cement with an intermediate ingredient also permeable to light, to constitute a composite sheet.

4. As a new article of manufacture, a transparency consisting of a self-sustaining 100 sheet or mass composed of separate parti-

cles combined in a preconceived design and united together by cement.

5. As a new article of manufacture, a transparency consisting of a sheet composed of separate particles including shells permeable to light disposed in edgewise assemblage and united together by cement.

6. As a new article of manufacture a translucent sheet composed of shells arranged in a preconceived design and united by a cementitious binder.

7. As a new article of manufacture a translucent self-sustaining sheet composed

of shells arranged in a preconceived design and united by a cementitious binder.

8. The art of manufacturing transparencies which consists in forming a transparent composite sheet, comprising a stratum of shells permeable to light and in edgewise assemblage, cemented together in any suitable design and cemented to transparent supporting sheets applied to each side of said stratum.

In testimony whereof, I have hereunto set my hand.

EDWARD H. PENCE.
